CLAIM

The ornamental design for a hand tool package, as shown and described.

DESCRIPTION

FIG. 1 is a front elevational view of a hand tool package showing my new design, the tool held by the package being shown in outline in phantom lines is shown for illustrative purpose only and forms no part of the claimed design;
FIG. 2 is a left hand side elevational view thereof, the right side elevational view being a mirror image thereof;
FIG. 3 is a rear elevational view thereof;
FIG. 4 is a bottom plan view thereof; and,
FIG. 5 is a top plan view thereof.
